JOHN J. HAHN, OF KANSAS CITY, MISSOURI, ASSIGNOR OF ONE-HALF TO FRANK L. COFIELD,
OF KANSAS CITY, MISSOURI.

GRAIN-DOOR FOR CARS.

No. 895,556.

Specification of Letters Patent.

Patented Aug. 11, 1908.

Application filed October 19, 1907. Serial No. 398,193.

To all whom it may concern:

Be it known that I, JOHN J. HAHN, a citizen of the United States of America, residing at Kansas City, in the county of Jackson 5 and State of Missouri, have invented certain new and useful Improvements in Grain-Doors for Cars; and I do hereby declare that the following is a full, clear, and exact description of the invention, such as will 10 enable others to make and use the same, reference being had to the accompanying drawings, forming a part of this specification.

To fulfil the demands for an efficient grain door for railroad cars, non-destructive 15 ability is one prerequisite. The door when closed must also be high enough to permit the banking of the grain upon either side of the car, afterward the grain seeks its own level. These doors should constitute a fixture with 20 the car and open sufficiently at the bottom to discharge a partial amount of the grain, and be made capable of folding back upon the inner side of the car so as to be entirely out of the way, thereby permitting freight of various 25 kinds to be transported in the car after the removal of the grain, without coming into contact with the door.

The above prerequisites constitute the principal objects of my invention. 30 The invention consists in the novel construction and combination of parts, such as will be first fully described and then specifically pointed out in the claims.

In the drawings, Figures 1 and 2 are views 35 of portions of the outer and inner side of the side walls of a car, adjacent to the opening for the door, showing views of the improved grain door from the outside of the car and also from the inside of the car, respectively, 40 the sections of the grain door being in a closed position. Fig. 3 is a view of portions of the inner side wall of the car, adjacent to the door opening, showing the sections of the main door folded against the side of the car 45 when not in use, and the upper auxiliary section of the door secured in an elevated position. Fig. 4 is a vertical sectional view taken upon the line x, x , on Fig. 3. Fig. 5 is a view in perspective of portions of the outer 50 side wall of the car adjacent to the door opening, broken away above the sections of the main and auxiliary doors, the latter being shown interlocking with main section, the lowest in position of these sections of the 55 door being shown partially open to discharge

the grain adjacent thereto. Fig. 6 is an enlarged view in detail of one of the door supporting rods or pintle posts, showing portions of the upper and lower folding sections of the door, and the telescopic hinges. Fig. 7 is a detail enlarged view in perspective of one of the latches on the sections of the folding doors. Fig. 8 is a horizontal sectional view of the lower section of the door in a closed position. Fig. 9 is a detail view in perspective of the door bolt. Fig. 10 is a detail view in perspective of a broken portion of the auxiliary section of door, showing the sliding connections.

Similar numerals of reference indicate corresponding parts in all the figures of the drawing.

Referring to the drawings, 12 indicates portions of the vertical outer side wall to the body of a car adjacent to the door opening, 75 and 13 indicates the door opening.

14 indicates the vertical inner side wall of the body of the car, adjacent to the door opening 13.

15 indicates the upright door posts or 80 jambs upon each side of the door opening.

17 indicates the roof supporting beam extending over the door opening 13, and in the longitudinal direction of the car, and secured to the upper ends of the door posts or 85 jambs, 15.

18 indicates the longitudinal floor supporting beam to the body of the car, extending beneath the door opening, and 19 indicates the floor.

20 indicates the roof of the car. 90
In the door jambs or posts, 15, toward the inner side of the car and opposite in position to each other, are recesses, 21, extending from the line of the floor, 19, upwardly to the beam 17. In these recesses are arranged in a vertical position, the supporting pintle posts or rods, 22, for supporting the main grain doors. These rods are stepped at their lower ends in the openings 23 in the floor. 95 The circumference of the rods at their lower ends is of considerable size. At a height above the floor, 19, in excess of one-third the distance toward their upper ends or at the shoulders, 22^x, these rods are reduced in circumference, as at 22°. The reduced upper end of the portions 22° are inserted within the openings 25, in the plates 26, which plates are secured fixedly to the under side of the roof supporting beam, 18, the openings 25 100 105 110

being slightly larger in circumference than the said portions 22° of the rods. Upon the floor 19 of the car, between the door jambs 15 and with its inner longitudinal surface in line 5 with the outer side of recesses 21, in posts 15, is secured a flat bar 27.

The grain door is made in separate parts, and consists of the lower hinged sections 28, and the upper hinged sections 29, these sectional parts of the door being hinged to the vertical rods 22 upon opposite sides of the door opening, and the outer portions of the sections of the door overlapping a short distance, as seen in horizontal sections in Fig. 8. 10 The sectional parts of the door are made preferably from metal plate, and consequently will sustain the greatest amount of rough usage. This usage is however avoided in the necessary steps taken to open the sectional parts of the door, and release the grain and fold them as hereinafter described. The hinge socket plates 30, to the lower contiguous sections 28, of the door, are formed from the inner vertical portions of the plates comprising said sections of the door, which portions are bent from the direction of the inner side of the posts or rods, 22, and extended between the said rods and the door jambs 15, thence extended in a curved line, concentric 15 with the surfaces of the said sections of the door, thereby leaving slots, $29^{\times}$, which are of sufficient width to permit the entrance of the plates forming the upper sections 29 of the door, the sections 28 extending in height 20 from the floor, 19, in the rear of the horizontal bar 27, to a position horizontally in line with the shoulders $22^{\times}$ of the rods or posts 22. The hinge socket plates, 31, to the upper sections 29 of the door are formed 25 in the same manner as the hinges, 30, to the sections 28, the inner ends of the plates forming the socket plates being extended loosely around the reduced portions 22° of the rods or posts 22, and closely to the outer surfaces 30 of the plates forming said sections 29, the outer circumference of the socket plate 31 being less than the inner circumference of the socket plate 30, so as to readily slide within, telescopically, the latter socket, the lower end of the socket 31 normally resting 35 on the shoulders $22^{\times}$ of the rods or posts 22, portions of the said lower ends of the hinges being cut away at $31^{\times}$ (see Fig. 2) to permit the lower portions of the section or plate 29 40 to extend downwardly or overlap upon the inner side of the upper portions of the lower section, 28, of the door.

In order to give rigidity to the sections 28 and 29 of the grain door, short portions 45 and 29 of the grain door upon one supporting rod or post, 22, are bent outwardly at right angles to form ribs, 32. The lower portion of the rib on the section 28 of the door is cut away at 33 the height of the bar 27 and upon one of the sections 29, the distance which the

said doors overlap on the section 28. The outer ends of the sectional parts 28 and 29 of the door mounted on the other vertical post or rod 22, are curved in a slight degree inwardly, so as to form a close bearing upon the inner surfaces of the sections having the ribs 32, as seen in Fig. 8. Upon the outer surfaces of the section 28 of the door, are secured the horizontal angle plates 34, in vertical series, spaced apart at equal distances from each other and the respective upper and lower portions of the sections of the door. Upon the upper section, 29, of the door, a single angle bar, 35, is placed on each section at a point a short distance downwardly from 70 the upper portion of the said section, and in line horizontally with each other.

36 indicates latches on the outer side of the upper and lower sections 28 and 29 of the door and comprising flat plates which are 85 provided with lugs, 37, at one end pivotally connected at $38^{\times}$ with the portions of the angle plate 34 upon the sectional parts 28 and 29 of the door, connected with one of the rods or posts 22, upon one side of the door 90 opening. The outer ends of the latches are provided with downwardly extended portions, $36^{\times}$, which engage with slots, 38, in the outwardly extended portions of the angle plates, 34 and 35, upon other sectional parts 95 of the hinges to the rod or post on the other side of the door opening 13, the latches passing the ribs 32 and 33 when the sections of the door are secured in position. In order to strengthen the rivet $38^{\times}$, a flat lug, 39, is secured to the under side of each latch, directly beneath the lug 37, and in the outwardly extended portions of the angle bars are slots, 40, in which the lugs enter when the sectional parts of the door are latched. Upon the 100 outer sides of the lower sectional parts 28 of the door are sliding bolts, 41. These bolts are located near the inner end and above the lowest angle bar, 34, on the lower section of the door, and the bolt casing is slotted at 42 105 in the upper side of the casing for the passage of the handle 43, so that the handle must be raised upwardly to release the bolt, the bolts serving to keep the lower sections of the door from being raised accidentally and engage 110 with the openings or keepers, 44, in the door jambs 15.

The auxiliary section, 45, of the door serves two purposes, one of which is to close the space of door opening, 13, above the sectional parts 29 of the door as much as necessary to permit the banking of the grain upon either side of the car, and also to add to the upper sectional parts of the door more resistance to the outward pressure of the grain. 115 This section 45 is preferably composed of a single plate, and extends horizontally from the inner side of one rod or post, 22, upon one side of the door opening, 13, to the inner side of post 22, upon the other side of said 120 125 130

opening the ends, 46, of the plate being curved in the arc of a circle so as to extend part way in the direction of the circumference of the upper portions 22° of the posts 22. This door is strengthened by a longitudinal angle bar, 45^x. The lower portions of the section 45 extend downwardly upon the inner side of the upper portion of the section 29 of the door a short distance, and from said portions extend outwardly the clips, 47, which clips are extended downwardly on the upper portions of the outer surfaces of the sectional parts, 29, of the door a short distance, and interlock with the said upper section 29, these clips being narrow in width and integral with the plates forming the section 45. The section 45 of the door extends upwardly to within a short distance of the beam, 17, at the upper end of the door opening, 13, and a longitudinal portion extending from the curved portion, 46, of the section or plate to the other portion, 46, is bent inwardly to form a socket, 48, the curved ends of the plate being cut away a short distance below the inner lines of the tube. From the ends of the socket extend upwardly the plates or leaves, 50, which form hangers to the section 45 of the door, their outer ends being curved forwardly in a slight degree. In the ends of socket 48 are inserted the inner ends of separate rods, 51, upon the outer ends of which rods are collars, 52, which fit loosely the portion 22° of the rods or pintle posts 22. Connected rigidly with the lower surface of the beam 17, at the upper end of the door opening 13, are rectangular shaped loops, 53, located near the door jambs 15, and in the direction of the inner side of the car.

In the lower portion of the section 45 of the door, at a point equi-distant from its ends, is an opening, 54, short in length (see Fig. 1). Upon the roof 20 of the car, is a block, 55, upon which are separate outwardly inclined springs plates, 56, for retaining the section 45 of the door, the lower ends of which plates extend downwardly a short distance and the lower portions are bent outwardly to form shoulders, 57, from which shoulders the remaining portions extend downwardly and inwardly, the block 55 being located in a position above the lower end of the section 45 when elevated.

When it is desired to remove the grain from a car equipped with the invention, the sections of the door being in a closed position as seen in Figs. 1 and 2, the bolts 41 are withdrawn from the openings 44 in the door jambs and the latches 36, upon the lower sections, 28, of door are released from their keepers 38 and turned upon their pivots in a reverse position, as seen in Figs. 3 and 5. A lever is then applied to the lugs 60, on the outer portions of the section 28, and the said sections of the door raised upon their hinges a height slightly above that of the bar 27, and under the pressure of the grain, the lower sections, 28, open outwardly and take the position as seen in Fig. 5. The amount of grain adjacent to the sections of the door which is discharged permits these sections of the door to be replaced in position in rear of the bar 27. The section 45 of the door is then moved directly upwardly to a position in which the hangers, 50, are opposite the loops 53. The lower end of the door is then raised in a horizontal position, the hanger engaging with the loops and the lower ends of the retaining springs, 56, entering the opening 54 in the section 45, and is retained by the shoulders 57 in an elevated position. The latch 36, on the upper sections, 29 of the door is then released and the lower sections, 28, raised upwardly, their upper portions coming into contact with the angle bars 35 on the sections 29, and both upper and lower sections of the door are raised directly upward as far as permitted in the door opening, and above the grain in the car, the hinges, 30, on the doors, 28, telescoping with the hinges 31, on the sections 29. The sections of the door in their elevated positions are then folded inwardly in the direction of and upon the inner side, 14, of the walls of the car, and the lower section 28 of the door placed within the hooks or keepers, 62, secured to the inner side of the wall. These operations are entirely accomplished from a position outside of the door opening, and from the necessity of securing the sections of the door in their folded positions before removing the bulk of the grain, a careful and methodical handling of the sections of the door is assured. When the cars are employed for various kinds of freight, the angle bars, 36, upon the doors, which are curved at the ends, not only shield the doors, but also afford protection to the inner side of the car, the doors in the formation of the hinges fitting closely against the inner side of the car. The springs, 56, supporting the auxiliary door 45 require to be drawn together simultaneously by the hands, so that accidental release of the door is prevented. The invention is applicable to door openings, other than for cars if preferred.

Having fully described my invention, what I now claim as new and desire to secure by Letters Patent is:

1. The combination with a door having separate hinged parts, of pivot posts supporting said hinged parts, and a sliding sectional member of said door upon the pivot posts locked to said separate hinged parts.
2. The combination with the wall of a car having a door opening upright pivot posts within said opening, a door having upper and lower sectional parts hinged to said pivot posts, fastening devices for said parts of the door with each other, and an auxiliary slid-

ing sectional part of the door upon said pivot posts, and devices on said auxiliary sectional part of the door engaging with the upper hinged sections of said door.

5 3. The combination with the wall of a car having a door opening, and with upright pivot posts within said opening, of a door having upper and lower sectional parts, socket plates mounted upon said pivot posts, 10 connected with the separate parts of the door, one of said socket plates having a slot and adapted to permit the entrance, telescopically, of the other socket.

4. The combination with the wall of a car 15 having a door opening and recesses in the sides of said opening, pivot posts within said recesses, a door having separate sectional parts, sliding hinged connections for the upper and lower parts of the door on said pivot 20 posts, a shoulder on said pivot posts for supporting the hinged connections for the upper sections of the door, and an auxiliary sectional part of said door, sliding hinged connections therefor on the pivot posts and clips 25 on the lower portions of said auxiliary section of the door, overlapping the upper portion of the separate sectional parts of the door.

5. The combination with the wall of a car 30 having a door opening and with pivot posts

within said opening of a door having upper and lower sectional parts, a vertical sliding plate extending transversely to said door opening, sliding collars on said pivot posts pivotally connected with said plate, said 35 plate having its end portions extending part way around the pivot posts.

6. In folding grain doors for cars, the combination with vertical rods or posts, and separate plates composing said doors, of sockets integral with said plates, varying in circumference, one of which sockets is provided with a longitudinal slot, said sockets being adapted to be extended within each other 40 telescopically.

7. The combination with the wall of a car having a door opening and with pivot posts within said opening, of a grain door having separate sectional folding parts, sliding devices on said posts adapted to be extended 45 telescopically within each other and connected with and supporting the separate parts of the door, and means on the wall of said car for retaining the doors in an elevated position.

JOHN J. HAHN.
